FIREARM

Eulalio M. Varona, Tacloban, Philippine Islands

Application July 7, 1936, Serial No. 89,375

2 Claims. (Cl. 42—19)

The invention relates to shotguns and more especially to single shot firearms.

The primary object of the invention is the provision of a firearm of this character, wherein the barrel is slidably fitted with the breech and such breech is relieved of a shell through the under side of the breech on moving the barrel within the breech, the barrel being locked in the breech in a novel manner and when the shell has been exploded it is readily ejected from the breech on the sliding of the barrel outwardly of the latter.

Another object of the invention is the provision of a firearm of this character, wherein the breech has fitted therein the firing pin, it being cocked in a novel manner and is released from a cocked position by a trigger, there being no hammer present in the assembly of the firearm and the breech and barrel are interfitted with each other so that the barrel can be operated for the loading and unloading of the breech, the loading and unloading being effected in a unique manner.

A further object of the invention is the provision of a firearm of this character, wherein the interfitted breech and barrel are such that the stock can be readily and easily detached from the breech without the necessity of special equipment or tools as the breech and the stock are joined with each other through the use of screws and such breech is loaded and unloaded from the lower side of the stock while the firing pin is set at one side of the firearm and a safety device cooperates with the firing pin setting means so that the said firearm can not be accidentally discharged or the load thereof fired until the setting means for the firing pin has been released from the safety device, the firing pin being released for the firing of the load by a trigger, the firing pin being built within the breech of the firearm.

A further object of the invention is the provision of a firearm of this character, which is simple in its construction, thoroughly reliable and efficient in its operation, readily and easily loaded and unloaded, safe from accidental exploding or firing, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a side elevation of a firearm con-

structed in accordance with the invention showing the firing pin cocked and latched for safety against firing.

Figure 2 is a bottom plan view of the breech having the stock and barrel removed therefrom. 5

Figure 3 is a side elevation of the same.

Figure 4 is a fragmentary bottom plan view of the barrel detached from the breech.

Figure 5 is a fragmentary vertical longitudinal sectional view through the firearm and the firing 10 pin released and in firing position.

Figure 6 is a horizontal longitudinal sectional view through the breech showing in detail the firing pin in firing position.

Figure 7 is a front elevation of the parts shown 15 in Figure 2.

Figure 8 is a sectional view on the line 8—8 of Figure 5 looking in the direction of the arrows.

Figure 9 is a sectional view on the line 9—9 of Figure 5 looking in the direction of the arrows. 20

Similar reference characters indicate corresponding parts throughout the several views in the drawings.

Referring to the drawings in detail, A designates generally a breech, B a barrel and C the 25 stock, respectively, of the firearm. This breech A is attached to the stock C by fasteners in the form of screws 10 and 11, respectively, so that these parts will be separably joined with each other. 30

The barrel B at its inner end is slidably fitted within the breech A which interiorly thereof constitutes a firing chamber 12 next to a breech block 13 which is made fast at 14 and through which works the firing pin 15 integral with a stop head 16 which has a stem 17 slidable in a tubular guide 18 built within the breech A constituted by a tubular cylinder 19. The stem 17 has surrounding it a coiled tensioning spring 20, the same being also in surrounding relation to the guide 18 for 40 the said stem and is concealed within the cylinder 19 rearwardly of the breech block 13 while the stop head 16 coacts with the breech block 13 when the pin 15 is advanced for the firing of the firearm. 45

At the under side of the breech cylinder 19 is a loading slot 21 which registers with a corresponding opening 22 in the stock C so that a cartridge 23 can be introduced into the firing chamber 12 and located in position therein to be exploded by the firing pin 15 when the firearm is shot. 50

The breech cylinder 19 forwardly of the loading slot 21 for the firearm is provided with a guideway 24 accommodating a keeper lug 25 on the barrel 55

B and this way at the forward and rearward ends thereof has lateral offsets 26 and 27, respectively, so that on the twisting or turning of the barrel when the lug 25 confronts these lateral offsets 26 and 27 the said lug will be engaged therein and thus holding the barrel in its shifted position. When the lug 25 engages in the lateral offset 27 it will be held latched within the breech cylinder 19 for closing the loading slot 21. Now to effect this latching, it being assumed that the barrel B has been pulled outwardly from the breech A and turned with the lug in the offset 26 of the way 24, it is necessary to release the lug 25 and align it with the way 24 so that by pushing inwardly on the barrel the said lug 25 will be brought to the offset 27 then by a turning of the barrel it will be fastened in a latched position and closing the loading slot 21 in the breech.

When the barrel is pulled outwardly of the breech A the loading slot 21 is open so that a cartridge can be introduced into the breech and when this cartridge has been so introduced on the pushing inwardly of the barrel B the said cartridge 23 is telescoped into the inner end of the barrel and thus in a position to be exploded by the firing pin 15 when operated for firing movement. The lug 25 has fitted therein a spring pressed friction latching ball 28 for engaging a seat or keeper notch 29 in one edge of the offset 27 of the way 24 so that when this lug 25 is within the offset 27 the barrel will be frictionally latched in its adjusted position.

The offset 26 of the way 24 opens into a mouth 29 clearing the lug 25 when the barrel has been pulled outwardly so that it can be separated conveniently from the breech A, particularly for the cleaning of the barrel and the breech.

Working through the breech at the opening 30 therein is a locking sear 31 for engaging the head 16 to cock the firing pin 15. This sear is carried on a leaf spring 32 holding it in a locking position to engage the head 16 when the pin 15 is moved to cocking position, the sear 31 being beveled at 33 for the tripping of the head 16 thereover on the cocking of the locking pin. The spring 32 is engaged by a trigger 34 which is manually operated for the unlocking of the sear 31 from the head 37 of the firing pin 15 when it is cocked, the spring 20 then being active for moving the pin 15 to firing position for exploding the shell 22 as fitted within the barrel B which is normally latched within the breech A and closing the loading slot 21 in the latter. The trigger 34 is within a finger guard 35 and such trigger is finger operated in the usual manner common to firearms.

The head 17 of the firing pin 15 has a setting finger 36 which protrudes through a slot 37 in the side of the breech cylinder 19 so that said finger 36 can be manually operated in the cocking of the firing pin 15. The slot is common to a keeper notch 38 receiving the finger 36 when in the notch 38 and thus safe locking said finger 36 when the said firing pin is held cocked. Working in the slot 37 at the rear end thereof and upon a guide 39 is a safety latching block 40, it being movable over and onto the finger 36 when in the notch 38 and thus safe locking said finger 36 when the firing pin 15 is in cocked position so that the firearm can not be accidentally exploded or fired. Pivotal fitted on the breech cylinder 19 for rocking movement upon a pivot 41 within a clearance 42 is a rear sight 43 while at the discharge end of the barrel is a forward sight 44, the rear

sight 43 being provided with an ejector nose 45 which rides the inner end of the barrel B when the latter has been pushed inwardly of the breech cylinder 19 to hold the rear sight 43 against locking movement. Then when the barrel B has been pulled outwardly of the breech cylinder 19 the ejector nose 45 rides off of the inner end of the said barrel B and automatically operates by the locking of the rear sight 43 in the clearance 42 to eject the shell 23 through the slot 21 for the ejecting of the shell from the firearm. This shell 23 when placed in the firing chamber 12 in the breech cylinder 19 to be received in the barrel 23 at its inner end is engaged by a spring detent or dog 47 to hold the said shell within the firing chamber for its telescopic fitting within the inner end of the barrel B when pushed inwardly of the breech A. The detent or dog 47 being adapted to ride upon the inner end of the barrel B when pushed inwardly of the breech A by initially fitting a cam faced notch 48 provided in the inner end of the barrel B which notch is disaligned with said detent or dog 47 when the barrel B is turned in the breech cylinder 19 to bring the lug 25 into the offset 27 of the way 24. Now when the lug 25 is turned out of the offset 27 of the way 24 this notch 48 is realigned with the detent or dog 47 so that it will engage with the cartridge 23 as contained within the firing chamber 12 in the breech A so that the said shell 23 will become ejected from the barrel B on the pulling outwardly upon said barrel and thus retaining the shell within the breech for the automatic ejecting of the said shell therefrom under the action of the rear sight 43 at the nose 45 thereof in that the spring 49 about the pivot 41 becomes active on the rear sight 43 causing the nose 45 to move inwardly of the clearance 42 and thus tilt the cartridge 23 within the breech A and thus freeing said shell or cartridge 23 from the detent or dog 47 so that it will become ejected through the loading slot 21 and companion opening 22 for delivery from the firearm. Of course, the shell or cartridge 23 is automatically ejected from the breech A after such shell or cartridge 45 has been exploded in the shooting of the firearm. The outward pull upon the barrel B will open the loading slot 21 in the breech cylinder 19 so that the exploded shell or cartridge 23 will be ejected from the breech through this slot.

When the firing pin 15 has been released from cocked position and the shell exploded by the impact of said pin therewith the head 16 of said firing pin abuts the breech block 13 within the breech A of the firearm and on abutment of such head the firing pin has been moved to its fullest extent to firing position, the pin 15 being protruded through an opening 50 therefor in the breech block 13 for protrusion into the firing chamber 12 to strike the firing cap of the shell or cartridge 23 for the exploding of the latter when the same is in loading position within the inner end of the barrel B and such barrel has been pushed within the breech A to that position shown in Figure 5 of the drawings.

As has been stated the finger 36 permits the manual cocking of the firing pin 15 and when the trigger 34 is actuated the pin is released for firing action for the exploding of the shell 23 when in loading position within the firing chamber 12 and telescoped within the inner end of the barrel B of the firearm, the firing pin 15 being uncocked by the sear 21 operated for release by the trigger 34.

What is claimed is:

1. A firearm comprising a stationary cylindrical breech forming a firing chamber interiorly thereof and having a slot in one side and opening laterally therefrom, a barrel slidably and removably fitting said breech and having a cartridge seat, a breech block fixed within the breech next to the firing chamber, a firing pin working through said block and having a stem provided with a stop head, the said head being adapted for abutting the block, a tubular guide built within the breech and slidably receiving the said stem, a coiled tensioning spring about the stem and said guide and active against the head, a setting finger on the stop head and projected through the slot exteriorly of the breech, a lug-like sear having clearance through the breech and provided with a beveled end for tripping engagement of the head therewith, a spring fixed exteriorly to the breech and carrying the sear for urging it into latching engagement with the stop head, and a finger-actuated trigger pivoted exteriorly to the breech and having engagement with a free end of the last-mentioned spring for actuating the sear in tripping the head for the release of the firing pin. 5 10 15 20 25
2. A firearm comprising a stationary cylindri-

cal breech forming a firing chamber interiorly thereof and having a slot in one side and opening laterally therefrom, a barrel slidably and removably fitting said breech and having a cartridge seat, a breech block fixed within the breech next to the firing chamber, a firing pin working through said block and having a stem provided with a stop head, the said head being adapted for abutting the block, a tubular guide built within the breech and slidably receiving the said stem, 10 a coiled tensioning spring about the stem and said guide and active against the head, a setting finger on the stop head and projected through the slot exteriorly of the breech, a lug-like sear having clearance through the breech and provided with a beveled end for tripping engagement of the head therewith, a spring fixed exteriorly to the breech and carrying the sear for urging it into latching engagement with the stop head, a finger-actuated trigger pivoted exteriorly to the 20 breech and having engagement with a free end of the last-mentioned spring for actuating the sear in tripping the head for the release of the firing pin, and means for slidably latching the barrel with the breech and adapted for latching 25 the said barrel in two positions.

EULALIO M. VARONA.
